UNITED STATES PATENT OFFICE

2,558,410

CLOTHESLINE AND SUPPORTING MEANS
THEREFOR

Elmer E. Andersen, Denver, Colo., assignor of ten
per cent to Donald E. Anderson and five per
cent to Donald F. Clifford, Denver, Colo.

Application June 7, 1948, Serial No. 31,429

8 Claims. (Cl. 211—119.10)

1

This invention relates to a clothes line construction comprising a multiple of individual clothes lines arranged in parallelism and has for its primary object to individually support the multiple clothes line and to provide means for adjusting the lines and placing them under individual tension.

Another important object of this invention is to provide means for supporting a multiple of clothes lines in a reliable and safe manner so that the weight of clothes hung on the line does not injure or break the lines but is transmitted to the line retaining members or poles.

Another important object of this invention is to provide means for taking up the slack in the clothes line and for supporting the clothes line in an efficient and sturdy fashion.

A meritorious feature of this invention resides in the provision of an arch supporting beam suspended above the line and carrying a transverse supporting bar adapted to engage and support the multiple of lines disposed in parallelism below the arch means.

These and ancillary objects and other meritorious features are attained by this invention, a preferred embodiment of which is set forth in the following description and illustrated in the accompanying drawings by way of example only, wherein:

Figure 1 is a view in perspective of the clothes line construction, the same embodying the principles of this invention;

Figure 2 is a vertical sectional view taken substantially on the longitudinal plane of line 2—2, looking in the direction of the arrows;

Figure 3 is a sectional view of the means provided for supporting the vertical bars;

Figure 4 is a cross sectional view of one of the horizontal supporting members, taken substantially on line 4—4 of Figure 1 and illustrating the means provided for taking up the slack in the clothes line and placing the lines under tension, said means being provided for each individual line;

Figure 5 is a cross sectional view of one of the horizontal supporting members, showing the means provided for attaching one end of each of the multiple of clothes lines; and,

Figure 6 is a sectional view taken on the line 6—6 looking in the direction of the arrows in Figure 1.

Referring now more particularly to the drawings, wherein similar characters of reference designate corresponding parts throughout, with particular reference to Figure 1, this invention,

2

10, is shown in supported association with standards or legs 12, 14, 16 and 18. The standards are preferably anchored in the ground by permanently setting the lower portions thereof in concrete 20, in order to maintain them in an upright vertical position. The upper portions of the standards terminate in concave supporting ends or saddle portions and retain in a horizontal position a pair of parallel tubular supporting bars 22 and 24. However, the pair of standards supporting each bar or tube 22 and 24 may be dispensed with and one standard may be employed and attached to the medial portion of the horizontally disposed supporting bars.

15 The supporting bars 22 and 24 have aligned apertures or openings 26 and 28 disposed in alignment therein. A multiple of clothes lines, such as rope or wire or the like, 30 are arranged between the supporting tubes or bars 22 and 24, the same consisting of a plurality of individual lines 32, which are arranged in parallelism between said bars. The lines 32 are at one end disposed through the transverse apertures 26 in the bar 22, the end being brought around the upper portion of the bar and twisted around the main body portion of the line as at 34. The opposite ends of the lines 32 are secured to a bolt or the like 36 by inserting the end of the line into the eye of the bolt and twisting the end around the main 20 portion of the line as at 38. The bolt or similar fastening member is inserted in the aperture 28 in the bar 24, with a suitable engaging nut 40 disposed on the threaded shank thereof. Thus, rotation of the nut 40 on the threaded shank 25 of the bolt 36 takes up the slack in the lines 32 and adjusts the tension thereon.

20 Means is provided for engaging the medial portion of the lines 32 and transmitting the weight of articles placed on the lines to the horizontally parallel bars 22 and 24 and comprises an arch supporting beam 40, having its ends suitably secured by welding or the like to the central portions of the opposed bars 22 and 24. A transverse bar 42 is suspended from the 25 medial portions of the arched beam 40 by means of a vertical connecting tube or rod 44. Depending from the transverse supporting tube or bar 42 are a plurality of guide hooks 46 within which the middle portion of the lines 32 is inserted and accommodated.

25 Thus, the arched supporting beam eliminates any possible sag in the line due to the weight of articles or the like placed thereon and the more weight or load placed on the lines will produce 30 a greater upward pull on the lines or wires

through the arched beams. Further, any slack in the lines may be taken up by the adjusting bolts and nuts 36 and 40 and the tension on the lines may be adjusted as needed and desired.

While the horizontally disposed bars 22 and 24 have been shown as supported by the standards, it is to be apparent that the standards may be dispensed with and the bars may be secured to vertical supports, such as walls or the like. Further, the supporting bars 22 and 24 may be replaced by any other suitable supporting means, which would retain the multiple of lines 30 in a horizontal plane.

From the foregoing description taken in conjunction with the drawings, it is to be apparent that there has been provided an apparatus, which will enable clothes and the like to be securely retained. However, though the preferable form of the invention has been shown and described, it is to be understood that certain changes may be effected thereon as coming within the spirit of the invention and in the scope of the appended claims.

Having described the invention, what is claimed as new is:

1. A clothes line support for use with a plurality of individual lines arranged in parallelism comprising an arched supporting beam supported longitudinally above the lines, a connecting bar depending from the medial portion of the beam and a transverse line engaging member horizontally supported by said connecting bar for detachable association with the plurality of lines.

2. A clothes line construction comprising a pair of parallel horizontally disposed bars, a plurality of individual lines arranged in parallelism between said bars, means for individually adjusting the tension on the lines, an arched supporting beam suspended above the lines and secured at each end to said bars, a line retaining member suspended from the medial portion of the beam and means carried by said member for engaging the lines.

3. The combination of claim 2 wherein said tension adjusting means includes adjustable fastening members transversely inserted through one of said bars, one end of said fastening members being looped to accommodate the lines inserted and secured therethrough.

4. The combination of claim 2 wherein a connecting bar depends from the medial portion of the beam and carries the line retaining member, said member being disposed transversely of the beam.

5. The combination of claim 2 wherein said

last mentioned means includes hooks depending from the member and spaced therein for detachably receiving the lines.

5 6. A clothes line construction comprising a pair of horizontally supported bars disposed parallel to each other and having aligned apertures receiving a plurality of individual lines arranged in parallelism, means for individually adjusting the tension on said lines, an arched supporting beam suspended above the lines and secured at each end to the pair of supported bars, a vertically disposed member depending from said arched beam, a transverse bar fixed to the lower end of said member and depending from the medial portion of said beam, and line carrying hooks on said transverse bar for detachably receiving and supporting the lines.

7. A clothesline support comprising a pair of parallel horizontally disposed and longitudinally spaced bars between which a plurality of parallel lines are strung, an arched supporting beam secured at its opposite ends to the bars, and a horizontal retaining member transversely carried by the medial portion of the beam for receiving and supporting the lines, said transversely disposed member being secured to said arched beam by means depending from said beam and attached to said transverse member.

8. A clothes line support for use with a plurality of individual lines arranged in parallelism comprising an arched supporting beam arranged above and forming a medial support for said lines, a horizontally disposed line retaining member arranged transversely of said lines, means for attaching said transversely disposed member to said arched beam, and means for detachably connecting said lines to said transversely disposed member.
